UNITED STATES PATENT OFFICE.

MOSES E. CHENEY, OF LA CROSSE, WISCONSIN, ASSIGNOR TO NATIONAL GAUGE & EQUIPMENT COMPANY, OF LA CROSSE, WISCONSIN, A CORPORATION OF DELAWARE.

INSTRUMENT-BOARD PANEL AND LIGHTING CONSTRUCTION.

Application filed July 21, 1928. Serial No. 294,521.

This invention relates to improvements in electric light sockets for instrument board panels and lighting constructions and more particularly those adapted for use on motor 5 cars.

The main feature is a light socket that can readily be applied to the modern instrument board and when so applied will be dust proof and incapable of being jarred loose 10 during the travel of the motor vehicle. Furthermore, the construction is such that the light socket is suitable for attachment to a panel having the commonly used shield for indirect lighting, and the shield is integrally 15 formed from the base panel, co-operating with the light socket to form a very satisfactory and efficient attachment and one that reduces the cost of construction besides dispensing with any projecting parts on the 20 front of the panel.

In this improved construction it is only necessary to notch one part of the rim of the light opening to be found in the standard panel of the modern motor car to make the 25 panel suitable for this improved light socket.

Other objects and advantages will be in part indicated in the following description and in part rendered apparent therefrom in 30 connection with the annexed drawings.

To enable others skilled in the art so fully to apprehend the underlying features hereof that they may embody the same in the various ways contemplated by this invention, 35 drawings depicting a preferred typical construction have been annexed as a part of this disclosure and, in such drawings, like characters of reference denote corresponding parts through all the views, of which:—

40 In the drawings Figure 1 is a front elevation of the instrument panel. Fig. 2 is a detail view of the light bulb socket, parts being shown in section; Fig. 3 is a sectional view of part of the panel showing the shield; 45 Fig. 4 is a front view of a portion of the panel. Figs. 5, 6 and 7 are detail views of the light socket and Fig. 8 is a detail of the gasket for the socket.

There is preferably shown the bulb 1 se- 50 cured to a stem 2 and this stem fits within the light socket housing 3 and is secured thereto by the bayonet joint 4. This housing 3 is preferably formed with two integrally formed fingers 5 projecting from the

housing. The fingers are shown spaced 55 apart about 120° and intermediate the fingers and evenly spaced therefrom there is shown a clip 6 which is formed in the shape of a hook. The fingers 5 extending inwardly toward the center of the housing but 60 at their outer ends are formed with outwardly projecting prongs 7 which are shaped to guide the fingers along the inner surface of the light shield 8 and the fingers are formed so as to be able to spring outwardly 65 when the light socket has been forced against the panel and these prongs 7 cooperate with the free edge of the rim of the shield to form stops which hold the socket 70 in place, requiring a tilting of the socket to bring about the disengagement from the shield as hereinafter explained.

The panel base is 9 and the light opening has a rim 10 and an upturned flange extends substantially half way around the rim, this 75 flange constituting the usual light shield 8 employed on the modern panel board for motor cars. This shield is preferably formed integrally with the base which makes an inexpensive and strong construction suitable 80 to cooperate with the spring pressed locking fingers heretofore referred to. A notch or recess 13 is formed in the rim of the opening 10 which is preferably rectangular in shape and of a size sufficient to form means 85 for positioning the light and when so positioned the hook 6 will drop into engagement with said notch or recess.

A compressible member 14, (see Figs. 7 and 8) which may be a cork gasket, is placed 90 over the spring arms 5 and the hook clip 6 is adapted to fit over said member 14, whereby said member will lie between the socket and panel when the parts are assembled into 95 position.

It will now be apparent that in order to apply this light socket to the panel it will only be necessary to position the parts so that the hook shaped clip 6 will drop into engagement with the notch 13 and then the 100 ends of the spring arms can be pressed inwardly so that they will enter the light opening and when the socket has been inserted to the limit of its movement the fingers 7 will spring outwardly thereby 105 binding against the outer rim of the flange 8 and the compressible member 14 will be firmly clamped between the socket and

panel. This construction, it will be seen, forms a dust proof member for protecting the inside of the panel instrument from dust and also preventing the parts from becoming loosened by jars incident to the travel of the motor car.

In order to disengage the light socket from the panel, it is only necessary to tilt the socket on its clip 6, as a hinge joint, thereby forcing the fingers inwardly and releasing the stops 7 from engagement with the rim of the shield 8.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention, and therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of United States:

1. In an instrument panel board and lighting construction the combination of a panel with an integral flange forming a light shield; a compressible member; and a unitary light socket with prongs extending therefrom the prongs being capable of fitting against the inner surface of the shield and thereby causing the compression of the compressible member.

2. In a device of the character specified the combination of a panel having instrument openings and light openings; a shield projecting from the light opening; a light socket with locking devices adapted to project within said light opening; and a compressible gasket between said socket and said panel, the locking devices being adapted to spring into locking position with the shield and thereby compress the gasket.

3. In a device of the character specified the combination of a panel with a light opening; a flange projecting from the panel to form a shield extending partially around

said opening; a light socket; locking arms on said socket; a seat adjacent the shield; a gasket between the socket and panel; and a clip on the socket capable of registering with said seat whereby the parts will be positioned to enable the locking arms to engage with said shield and clamp the gasket to said device.

4. In a device of the character specified, the combination of a panel having a shield and a seat adjacent thereto; a socket with locking members comprising a part to engage with said seat and with said shield whereby the socket can be applied directly to the panel and can be tilted on said seat for the purpose of disconnecting said socket from the panel.

5. In a device of the character specified, a panel with light openings; a shield about an opening extending partially around same; a light socket having spring arms and a hook shaped clip; said panel being formed with a seat adjacent said shield; said arms being formed with curved ends whereby the arms can be pressed into said light opening by positioning the hook and seat together and the curved ends will thereafter be sprung into engagement with the rim of the shield.

6. In a device of the character specified, a panel with light openings; a shield about an opening extending partially around same; a light socket having spring arms and a hook shaped clip; said panel being formed with a seat adjacent said shield; said arms being formed with curved ends; and a compressible member projecting from said socket and capable of being clamped against the panel when said hook and seat are brought into engagement and said curved ends brought into contact with the rim of the shield.

7. In a device of the character described, the combination of a panel having a light opening therein, with a light socket having arms inclined towards its center and capable of entering said opening, means for positioning said socket on said panel whereby said arms can be sprung into said opening; and means for securely holding said arms against outward movement.

In witness whereof, I have hereunto subscribed my name.

MOSES E. CHENEY.
